Patented Aug. 10, 1976

240,914

AUTOMOBILE FRONT FENDER

Jan Einar Wilsgaard, Torslanda, Sweden, assignor to
AB Volvo, Gothenburg, Sweden

Filed Dec. 20, 1974, Ser. No. 535,115

Term of patent 14 years

Int. Cl. D12—16

U.S. Cl. D12—184

FIG. 1

FIG. 2

FIG. 3

FIG. 1 is a perspective view of the outside of an automobile front fender showing my new design;

FIG. 2 is a perspective view of the outside thereof taken diagonally from the front; and

FIG. 3 is a perspective view of the inside thereof taken diagonally from the rear.

I claim:

The ornamental design for an automobile front fender, as shown.
